SELECTIVELY CONTROLLABLE REVERSING SYSTEM FOR TOY TRAIN CONTROL

Marshall H. Frisbie, Hamden, Conn., assignor to The A. C. Gilbert Company, New Haven, Conn., a corporation of Maryland

Application February 14, 1952, Serial No. 271,458

2 Claims. (Cl. 104—151)

This invention relates to improvements in electrical systems in toy railroads that utilize for feeding current to a toy train control circuit a manually operated voltage varying step-down transformer that is stationed usually at the track side. The present improvements are of use particularly in connection with toy railroads having two-rail track.

I have chosen for illustrating the invention a toy transformer of the general kind disclosed in a co-pending application of William R. Haury, Serial No. 227,897, filed May 23, 1951, now Patent No. 2,661,461, owned by the assignee of the present application, along with a toy train carried propulsion motor and train carried motor direction reversing relay of the electromagnetically stepping type disclosed in United States Patent No. 2,196,319, granted April 9, 1940, to J. E. McLoughlin, which patent also is owned by the assignee of the present application.

An object of the invention is to avoid unwanted reversing of the direction of running of the train carried propulsion motor as a necessary result of shifting the transformer control handle to train stopping position.

Heretofore in the manual operation of a variable transformer for starting, stopping and determining the speed of running of toy electric trains through the action of a train carried, motor reversing, electromagnetically stepped relay, the armature of the relay has performed a motor reversing automatic stepping movement each time the operating handle of the voltage varying transformer is swung to train stopping position. At each such occurrence the direction of running of the train has been reversed so that on successive renewals of current supply to the track the train is caused alternately to run forward and backward.

A specific object of the present improvement is so to condition a toy train circuit electrically in the normal zero speed, or train stopping, position of a voltage varying transformer control handle that the propulsion motor of the train can sufficiently be deprived of current to cause the train to come to a stop without at the same time or of necessity depriving the train carried relay solenoid of enough current to permit its armature to perform a train reversing contact action the next time the track voltage is increased to a train running strength.

An electrical system by which this result can successfully be attained is described hereinafter with reference to the appended drawings wherein:

Fig. 1 is a side view of a voltage varying transformer especially adapted for practicing the invention with its casing partially broken away to expose some of the interior parts.

Fig. 2 is a fragmentary plan view taken in section on the plane 2—2 in Fig. 1.

Fig. 3 is a fragmentary view in rear elevation looking in the direction of the arrows from the plane 3—3 in Fig. 1.

Fig. 4 is a fragmentary view of a top portion of the transformer case.

Fig. 5 is a wiring diagram of a complete electrical sys-

2

tem embodying the invention, in which is included schematically the variable voltage transformer of Figs. 1-3.

Full details of suitable mechanical construction for the circuit controlling toy transformer are contained in the aforesaid Patent No. 2,661,461, while full details of a train carried relay or electromagnetically operated step switch for automatically starting, stopping and reversing the direction of running of the train propulsion motor are disclosed in the aforesaid United States Patent No. 2,196,319. Hence there is illustrated herein only as much of the physical structure involved as is necessary to explain the present system improvements. The train carried parts that operate in the system are represented only diagrammatically in Fig. 5.

The framework 12 of the train controlling step-down toy transformer is preferably of insulative material and provides a vertical bearing 17 which guides a plunger shaft 18 and permits rotary as well as upward and downward sliding movement thereof. Plunger shaft 18 forms part of a mechanism which operatively couples a manual transformer control handle 19 with a current takeoff conductive wheel 20. The latter rolls across and in contact with an arcuate track 23' of current taps formed by baring the side-by-side insulated wires of the secondary coil 23 of the transformer. A laminated core 24 carrying the primary winding 59 and two-section secondary winding comprising series sections 23, 22, and parallel section 150 of the transformer is stationed on posts 25 within the housing of the framework. Core 24 may also carry wound around it a resistance wire 70, hereinafter referred to, either in conjunction with or in place of the section 22 of the secondary winding.

To serve as a voltage varying or voltage selecting member, take-off wheel 20 is rotatably carried at the end of a sweep arm 26 in a manner to sweep along the arcuate track 23' in an arc centered at a stationary pivot 27 that is fixed on and insulated from the transformer core 24 by means of a bridge bar 30 of insulating material. Sweep arm 26 comprises a thin resilient metallic leaf conductor that is biased to flex upward so that take-off wheel 20 tends to be lifted thereby out of contact with the track of current taps 23' at all points in its arcuate path of swinging movement. The tail end of sweep arm 26 is in permanent electrical connection with a flexible take-off lead 31 which trails the swinging movements of the sweep arm.

The movements of sweep arm 26 to various voltage determining positions are caused and/or permitted by a superimposed resilient leaf type of actuating arm 32. This arm is carried fixedly on the flattened lower end of plunger shaft 18 by means of a hub 34 having a hole correspondingly flattened to fit the shaft tightly. Actuating arm 32 is provided with turned down flanges 33 spaced widely enough apart to flank loosely the edges of sweep arm 26 so that bind preventing, free, relative, longitudinal, sliding movement between sweep arm 26 and its actuating arm 32 is permitted between the flanges 33. Sweep arm 26, however, is caused to follow the swinging movement of the actuating arm 32 at all times and can be flexed downward into its position shown in Fig. 3 against its inherent tendency to rise by superior flexural strength of arm 32. While depressed into the position shown in Fig. 3 take-off wheel 20, preferably made of carbon, rolls across and in conductive contact with the current taps or bared wire surfaces of the transformer secondary coil 23 in arcuate track 23'.

Fig. 1 shows in broken lines an upwardly slanting position of control handle 19 to which the latter will be swung automatically about a pivot pin 44 by the upward pressure thereagainst of plunger shaft 18 when handle 19 is released by the hand of the operator. Pivot pin 44 is fixed in the turret head 40. The upward thrust of

shaft 18 on handle 19 is caused by the axial expanding tendency of a spring 36 in the hollow 38 of the turret head, which spring presses upward against a thrust collar 37 fixed on plunger shaft 18. Spring 36 is sufficiently weak to yield downward to the weight of an operator's hand on handle 19. This normally depresses plunger shaft 18 to its full line position in Fig. 1. It may, if desired, fasten a spring clip 35 on the turret head which will receive and tend to restrain handle 19 in its full line position against the lifting tendency of spring 36, so that upward swinging of the handle to its broken line position requires lifting of the handle deliberately by hand. In the broken line position of handle 19, actuating arm 32 is elevated and this permits sweep arm 26 to flex upward sufficiently to lift take-off wheel 20 off and out of contact with track 23' at any point therealong.

Turret head 40 is a hollow rotary body preferably of insulating material and turns in unison with the horizontal swinging of control handle 19. By serving as a hub for this handle it enables the latter to be swung from side to side because of its own freedom to swivel with a rotary fit on the external surface of frame bearing 17. Turret head 40 is caused to swing horizontally by means of handle 19 because the latter occupies a diametrical channel 21 in the former. The turret head is held down in the frame well 14 by any suitable number of retaining screws such as 41 which extend slidably through arcuate slots 42 in the floor wall of the well so as to permit free but limited rotary movement of the turret head.

On turret head 40 there is carried externally a radially projecting spur 50 adapted to serve as an index pointer. This spur cooperates in its indicating function with an arcuate scale 51 of graduations on the casing of the framework which graduations are suitably marked by indicia to designate make-believe speed of the train in miles-per-hour. Spur 50 can also serve to limit the swinging of the handle in opposite rotary directions by engaging with a frame carried stop stud 52 located at the "full speed" end of scale 51 and by engaging with another frame carried stop stud 52' located at the "train stopped" end of the scale.

A novel feature of the present improvements in toy train operating system is preferably incorporated within the casing of the toy train controlling transformer. This includes a resistor 70 permanently connected in circuit by means of lead wires 71, 72, wire 71 leading to a conductive terminal plate 62 that is contactable by take-off wheel 20 in the low voltage position of the latter's travel and wire 72 leading to a low voltage point between section 23 and section 22 of the secondary winding. The other or high voltage end of secondary winding 23 is connected directly to a similar terminal plate 61 which likewise is contactable by take-off wheel 20 at the opposite limit of the latter's travel.

Current is furnished to rail 63 of the two-rail toy track from the sweep arm 26 through the flexible lead 31. The other rail 64 of the track forms a return path for the current to terminal plate 62 of the transformer by means of a lead 73.

Constantly completing a circuit across track rails 63 and 64 there is the solenoid 131 of a conventional train carried toy electromagnetic step switch or relay, designated 132 as a whole, which relay as hereinbefore mentioned may be constructed as shown in Figs. 2, 3, and 4 of the drawings in U. S. Patent No. 2,196,319. Relay 132 is carried on any toy rolling stock 149, such as the locomotive of a toy train. A conventional, train carried, A. C.-operated, propulsion motor 145 is electrically and mechanically connected in any conventional way to impel the traction wheels of the locomotive or other rolling stock. Motor 145 is sequentially started, stopped, reversed, and then stopped again, by increments of unidirectional rotary movement of a contact drum 146 in relay 132. This drum is advanced step by step by means of repeated reciprocal stroking excursions of an armature pawl 135.

On alternate electromagnetically impelled downward strokes pawl 135 engages and pushes on successive teeth of a ratchet wheel 139 that is fixed on contact drum 138. Such strokes of pawl 135 are effected by the magnetic attraction of the solenoid for its armature 135 and are yieldingly opposed by the armature returning spring 137.

The motor starting, stopping and reversing action of contact drum 146 is well known in the art and further will be apparent from the diagram of circuit connections in Fig. 5. If preferred, the step switch 132 may be constructed in accordance with drawing Figs. 3 to 10, inclusive, of my U. S. Patent No. 2,348,616.

Its armature may be caused to stroke away from the solenoid by a spring 137 or by the weight of gravity. It may be constructed to impel the teeth of the ratchet wheel either by its solenoid attracted stroke or by its retractive stroke, the opposite stroke in each case being idle in respect to the ratchet wheel. In either case a repetition of the complete upward and downward excursion of the armature is necessary in order to repeat a current switching increment of rotary movement of the contact drum 146.

Within the transformer housing 12 there is an extension 22 of the secondary winding 23 which, when sweep arm 26 and handle 19 are in train stopping or "off" position, furnishes to the track through resistor 70 a potential less than any range of voltage that will enable motor 145 to impel the rolling stock 149.

Also in the transformer about the core 24 there is an auxiliary secondary winding 150 that permanently, and independently of the positions of sweep arm 26, furnishes sufficiently high voltage to an extra binding post 151 of the transformer to feed current therefrom to stationary track side accessories such as crossing signals, track switching electromagnets, etc. from which accessories current can return to the transformer through rail 64 of the track.

Other electrical elements in the transformer whose purpose and arrangement are more particularly explained in Patent No. 2,661,461, are a voltmeter 53, an ammeter 54, a low voltage binding post 66, an overload protective circuit breaker 65, a red signal lamp 57 and a green signal lamp 58. The transformer windings are adapted to receive alternating current from an ordinary 60 cycle house line at, say 110 volts, through an attachment cord 152. A switch 153 may be provided in the attachment cord for cutting off current to the transformer without pulling the receptacle plug 154.

In operation the train will be stopped on the track whenever control handle 19 of the transformer 12 occupies a position wherein its index pointer 50 registers with the zero mark on the scale 51 of miles-per-hour indicia in Fig. 4. The train will also be stopped whenever the control handle 19 is lifted to its upwardly inclined broken line position in Fig. 1 whatever may be the track sweeping position of take-off roller 20 between the limits of its swinging movement shown in broken lines in Fig. 2. For causing the train to run, control handle 19 will be depressed into its full line position in Fig. 1, wherein it can yieldably be held if desired by the spring clip 35. In this horizontal position of the control handle it may be swung clockwise toward its position shown in Fig. 4 any degree of intermediate swinging movement until the index pointer 50 reaches the frame stop 52. In this position of the control handle, take-off wheel 20 will have been rolled along its conductive track 23' to its broken line position resting on terminal plate 61 in Figs. 2 and 3. This will cause the maximum voltage that can be induced in the transformer secondary 23-22 to be delivered to the toy railroad track 63, 64 through sweep arm 26 and lead 31. This maximum voltage of, say, sixteen volts can be reduced in small train speed reducing increments to a potential that is within the range, say, of one to six volts as the take-off wheel 20 sweeps along track

23' counterclockwise in Fig. 2 until it arrives in contact with terminal plate 62 as shown in broken lines in Figs. 2 and 3. Potentials between seven volts and sixteen volts are examples of a selected range of track voltage throughout which the propulsion motor 125 of toy train rolling stock 149 is adapted to be energized sufficiently to impel the train. However a potential, say, of five volts delivered at terminal plate 62 when index 50 points to zero miles per hour on scale 51 is within the aforesaid range of one to six volts that is below the above said range of train running voltage, and in this lower selected range of, say, one to six volts, the solenoid 131 of the stepping relay 132 if wound for example with about 950 turns of No. 31 A. W. G. gage of copper wire, a resistance of about 16.7 ohms, will continue to attract its contact stepping armature 135 with sufficient magnetic force to maintain the latter in its broken line position in Fig. 5 against the constant retractive pull of spring 137.

Hence in the above said zero position of index pointer 50 the train as usual will be stopped on its tracks until control handle 19 is again swung clockwise in Fig. 4 to increase the track voltage and cause the train to be restarted. But when so restarted, the train will run in the same direction as it did before it was stopped because in the absence of a stepping excursion of armature 135 the direction reversing contact drum 146 of relay 132 has not been advanced rotatively so as to reverse the direction of supply of current to motor 145.

It is the new principle of this invention that motor reversing can be accomplished only by lifting control handle 19 into its broken line position in Fig. 1 whereupon the track 63, 64 will be deprived of all potential or of so much potential that solenoid 131 will become sufficiently deenergized to release armature 135 to the retractive pull of spring 137. This lifts the armature to its full line position in Fig. 5 and now, when current is next restored to the track by depressing handle 19, not only will the train be started by a solenoid attracted downward stroke of relay armature 135 but the accompanying stepping of the contact drum 146 an increment of its turning will have caused reversal of current supply through the motor 145 whereupon the latter impels the rolling stock 149 in a direction opposite to that in which it was traveling before last being stopped.

The invention thus involves a specially equipped train controlling variable transformer a part of whose secondary 25 with resistance wire 70 combined therewith or substituted therefor normally continues to supply sufficient low voltage to the track after the train is stopped thereby to prevent train reversing action of relay 132 and yet which can be manipulated in a special manner at any time thereby to reverse the direction of train running by purposely cutting off all current to the track and restoring it again.

The present improvements can be embodied in various structures and electric circuitting arrangements falling within the principles of the invention and differing from those herein illustrated and described but that will be suggested by the disclosure hereof, wherefore the appended claims are directed to and intended to cover all fair equivalents coming within the broadest interpretation of the language in the claims.

I claim:

1. An electrical system for starting, stopping and varying the speed and direction of running of toy railway rolling stock by manipulation of a single handle in a remote controller of current supplied to the railway track, comprising, track-borne toy rolling stock carrying a variable speed reversible alternating current propulsion motor having circuit connections by which to derive current from the track, a variable transformer connected to supply alternating current at variable voltage

to the track having a control handle manually shiftable in a voltage reducing path and in a current cut off different path for stopping said motor respectively without or with reversal of the direction of subsequent running thereof, a current take-off member differently actuated by shifting of said control handle in said different paths, a series of separately insulated voltage taps in said transformer arranged to be contacted successively by said take-off member when the latter is actuated by shifting of said handle in said current reducing path, means to prevent shifting of said handle in current reducing direction in said current reducing path beyond a position at which a predetermined minimum voltage is supplied to the track insufficient to propel the rolling stock, a stepping switch carried by said rolling stock having electric contacts operative to make and break and reverse said circuit connections between said motor and the track, and a stroking electromagnet operative to step said switch to reverse said circuit connections responsively to cut off of current from said track including a solenoid deriving energizing current from the track so electrically wound that said electromagnet is insufficiently responsive to reduction of track voltage to said predetermined minimum to step said switch, whereby motor reversing stepping action of said switch responsive to shifting of said handle in said current reducing path is prevented.

2. An electrical system for starting, stopping and varying the speed and direction of running of toy railway rolling stock by manipulation of a remote control means 30 supplying current to the railway track, comprising, track-borne toy rolling stock carrying a variable speed reversible alternating current propulsion motor having circuit connections by which to derive current from the track, a variable transformer connected to supply alternating current at variable voltage to a circuit including the track, control means for stopping said motor without or with reversal of the direction of subsequent running thereof including manually shiftable means to vary the voltage in said circuit and also manually operable means 35 to interrupt said circuit, stop means mechanically associated with said voltage varying means in a manner to prevent manual shifting of the latter in current reducing direction beyond a position at which a predetermined minimum voltage is supplied to the track insufficient to 40 propel the rolling stock, a stepping switch carried by said rolling stock having electric contacts operative to make and break and reverse circuit connections between said motor and the track, and a stroking electromagnet operative to step said switch to reverse said circuit connections responsively to cut off of current from said track including a solenoid deriving energizing current from the track so electrically wound that said electromagnet is insufficiently responsive to reduction of track voltage to 45 said predetermined minimum to step said switch, whereby motor reversing stepping action of said switch responsive to shifting of said voltage varying means is prevented.
